(57) **CLAIM**

The ornamental design for a handle for a folding hand tool with opposing channels, as shown and described.

DESCRIPTION

FIG. 1. is an isometric view from the upper right front of a handle for a folding hand tool with opposing channels, showing my new design;

FIG. 2. is a top plan view thereof;

FIG. 3 is a right side elevational view thereof;

FIG. 4 is a bottom plan view thereof;

FIG. 5 is a left side elevational view thereof;

FIG. 6 is a front end elevational view thereof; and,

FIG. 7 is a rear end elevational view thereof.

1 Claim, 2 Drawing Sheets
